UNITED STATES PATENT OFFICE.

ALBERT POTTS, OF PHILADELPHIA, PENNSYLVANIA.

BARBED METALLIC FENCING.

SPECIFICATION forming part of Letters Patent No. 296,060, dated April 1, 1884.

Application filed October 16, 1883. (Model.)

To all whom it may concern:

Be it known that I, ALBERT POTTS, of Philadelphia, in the county of Philadelphia and State of Pennsylvania, have invented a new 5 and Improved Barbed Metallic Fencing, of which the following is a full, clear, and exact description.

My invention consists of an improved contrivance for securing wire barbs to metallic 10 fencing-strips in a simple, cheap, and efficient way, whereby the strips, which are more desirable for use than wires, may be armed with wire barbs, which are better than points cut out of the edge of such strips, my method of 15 connecting the barbs being cheaper and more efficient than other means of providing such strips with barbs, and also cheaper and better than the means of barbing wires, all as hereinafter fully described.

20 Reference is to be had to the accompanying drawings, forming a part of this specification, in which similar letters of reference indicate corresponding parts in both the figures.

Figure 1 is a perspective view of a thin flat 25 metallic strip as I prepare it for receiving the barbs, and Fig. 2 is a perspective view of a barbed strip constructed according to my invention.

I take a thin flat strap, *a*, of metal, and make 30 notches *b* in the edges at suitable distances apart and at opposite points, and secure pointed wire barbs *c* thereto, by providing wires *d* of suitable length with pointed ends, bending said wires double at the middle in the form of 35 wire staples, placing the wires across the strip from notch to notch, and twisting the ends together, so as to draw the bend of the staple

into one notch and to twist the wire into the other notch, thereby firmly securing the barbs in a very simple way, and in a very permanent manner, well adapted to hold the barbs securely as long as the metal lasts. The points 40 may be placed alternately in opposite directions, and the strips may be twisted, if preferred, as other metallic strips are.

Flat-strip fencing is much preferred to wire, 45 because of being more conspicuous to animals, and therefore less liable to be damaged and to damage animals by not being seen, and for other reasons; but the barbs formed on it by cutting the edges are very inferior, and so far no such simple and efficient method of attaching other points has been contrived as to enable such strips to be used with attached 50 barbs.

I am aware of the application to a fence-strip of pointed wires looped and twisted thereon, and of a pointed wire intertwined with a second wire, the ends of which second wire are bent over the edges of the fence-strip. 55

Having thus described my invention, what I 60 claim as new, and desire to secure by Letters Patent, is—

As an improved article of manufacture, a metallic fencing-strip, notched upon its edges, 65 combined with pointed wire staples, the said staples being secured in place in the notches by twisting their pointed ends together, substantially as shown and described, whereby barbs are formed upon the metallic strip.

ALBERT POTTS.
